UNITED STATES PATENT OFFICE.

JOZEF SIEMIECZKO, OF KINGSTON, WEST VIRGINIA.

MOUSE-TRAP.

1,288,712.

Specification of Letters Patent. Patented Dec. 24, 1918.

Application filed June 8, 1918. Serial No. 238,914.

To all whom it may concern:

Be it known that I, JOZEF SIEMIECZKO, a citizen of Poland, residing at Kingston, county of Fayette, and State of West Virginia, have invented certain new and useful improvements in Mouse-Traps, of which the following is a specification.

This invention relates to improvements in mouse traps and has as its special object the provision of a trap which is practically self setting, so that after having been sprung, it will reset itself into position to capture succeeding animals.

A further object is to provide means in which the captive animals are retained until a convenient time for their disposal.

These and other like objects are attained by the novel construction and combination of parts hereinafter described and shown in the accompanying drawing, forming a material part of this disclosure, and in which:

Figure 1 is a vertical sectional view taken on line 1—1 of Fig. 2.

Fig. 2 is a plan view and horizontal section of the trap, the section being taken on line 2—2 of Fig. 1.

Fig. 3 is a fragmentary transverse sectional view taken on line 3—3 of Fig. 2, and

Fig. 4 is an enlarged, fragmentary sectional view, showing the operative means employed.

The body 10 of the trap is here shown to be substantially rectangular, and formed with lowered front and side edges respectively 11 and 12, inclosing the entrance portion 14 of the body, which reaches substantially to the center of the trap, and open to a semi-circular recess 15 in the body.

Journalized in the sides 12 is a transverse spindle 17, at the axial center of the recess 15, the spindle extends through at one end and has formed with it a crank 18, having a handle 19 by which it may be rotated.

Secured upon the spindle is a wooden cylinder 20, having upon it, at one end, the inner coil of a helical flat spring 22, the outer coil of which is engaged with a fixed rod or pin 23, set in the frame, and adjacent to the spring on the spindle is a ratchet 24, engaged with a pawl 25, pivoted in the frame, the arrangement being such that as the spring is wound, the ratchet holds the spring under tension until the pawl is released.

Secured in the cylinder 20 are four radial plates 28, having cut-out portions 29 to provide room for the spring 22, the plates be-

ing otherwise essentially rectangular and adapted to rotate within the recess 15.

Secured in the horizontal plane of the spindle 17, between the sides 12, fixed to the wall 11 is a fixed narrow plate 30, containing a slot 31, adjacent to which is a raised bracket 32, carrying a pin 33 on which is pivoted a lever 34, formed at its outer extending end with a reentrantly curved, spring loop 35, while the lower, bent end 36 of the lever is formed into a sphere 37, operatively engaged within an opening 38, in a sliding detent 40, movable below the fixed plate 30 and held thereagainst by a rigid bracket 41.

Fixed in the outer end of the sliding detent 40 is a pin 43 normally drawn below the outer edge of the plate 30 by a coiled tension spring 44, fixed in the bracket 41 at one end, and with the pin 43 at the other.

Secured upon each of the rotatable plates 28 are brackets 50 in which, journaled on the pins 51, are bell crank levers, one of their arms 52, carrying a lure or bait 53, while the other arm 54 has an outwardly bent extension 55, having a detent lug 56 at its extremity, adapted to make contact with the curved loop 35 as the plates 28 are moved past. A stop bar 57 is engaged with the bell-crank lever so as to limit the movement of the lever.

Movable in a recess formed in the bottom of the body 10, so as to pass transversely across the opening 14, is a plate 60, having a central opening 61, and operable by the handle 62. This plate is also recessed longitudinally and adapted to receive an interior sliding plate 64, having a handle 65, while attached so as to extend below the plate 60 is a netted wire basket 66 which, when the inner plate 64 is withdrawn, receives the animal caught in the trap and maintains the same therein.

In operation, the spring 22, having been wound by the extending handle 19, until sufficient tension has been attained, and the pawl 25 raised, the structure is in condition for operation. Upon an animal entering upon the exposed plate 28, as shown in Fig. 1, and moving the lure so as to release the detent 56 from the bent loop 35, the spring 44 immediately retracts the plate 40, releasing the rotatable plate 28, allowing it to move down under the impetus of the spring 22, carrying with it the animal or whatever may be resting upon its upper surface,

so that the same will be deposited within the basket 66, it being understood that at that time the transverse cover plate 64 will have been withdrawn.

- 5 When the next succeeding plate arrives at a horizontal position, the end of the lever 55 makes contact with the extending loop 35, pressing the same rearwardly and through the lever connection 36, presses the top plate 10 40 outward so as to intercept and prevent further movement of the next plate 28 the detent 56 on the next plate automatically engaging with the end of the loop 35 so as to reset the trap.
- 15 When it is desired to remove the animal caught within the basket 66, the sliding plate 64 is placed in position, the handle 62 withdrawn, together with the plate 60 and basket so that the animals caught may be 20 disposed of in any convenient manner.

Having thus described my invention what I claim as new and desire to secure by Letters Patent, is.

1. In a mouse trap, the combination with 25 a body having a through opening, and a semi-circular recess in its rear portion, of a spindle mounted transverse in said body at the axial center of said semi-circular recess, a spring operatively engaged with said 30 spindle, a plurality of radially disposed plates secured to said spindle, bell-crank levers mounted upon the upper surfaces of said plates, lures engaged therewith, a sliding detent engageable with said plates 35 whereby they are held successively in a horizontal position, means for actuating said detent and means combined with said bell-crank levers on said plate for operating said actuating levers, whereby said plates 40 are consecutively released and allowed to rotate from a horizontal to a vertical position.

2. In a mouse trap, the combination with 45 a body, a spindle mounted transversely therein, a plurality of plates engaged radially with said spindle, and means for normally rotating said spindle, of a sliding detent arranged in said body adapted to intercept said plates, bell-crank levers for

retracting said sliding detent, resilient 50 means for drawing said detent rearwardly, a fixed narrow plate in the horizontal plane of said spindle, a raised bracket on said plate, a lever pivoted on said bracket, a spring loop combined with said lever, lures 55 engaged with said bell-crank levers, means for releasing said detent upon the movement of said lures by an animal, and for consecutively releasing said plates for rotation 60 from a horizontal to a vertical position, and means adapted to be brought into contact with said loop for resetting said detent so as to engage with the next succeeding plate for resetting said trap.

3. A mouse trap comprising a casing, a 65 spindle journaled transversely therein, and a spring engaged with said spindle whereby it is rotated, of means for tensioning said spring, a plurality of radially disposed plates secured to said spindle, a casing in 70 which said plates rotate, a movable detent engageable with each of said plates, a lever for actuating said movable detent, a spring loop combined with said lever, bell-crank 75 levers mounted upon the upper surfaces of said plates, lures engaged therewith, means for actuating said detent, and means combined with said bell-crank levers, whereby said plates are consecutively released and 80 allowed to rotate from a horizontal to a vertical position, and a receptacle for the caught animal.

4. In a mouse trap, the combination with 85 a plurality of rotatably mounted plates, and means for normally holding said plates in an operative position, of means for rotating said plates, means operable by a lure for releasing said plates, a plate removably mounted in the trap, a netting into which the animals are delivered suspended from said plate, said plate having a central opening, and a removable closure for closing said opening when the plate and netting are removed.

In testimony whereof I have affixed my 95 signature.

JOZEF SIEMIECZKO.
